UNITED STATES PATENT OFFICE.

ED SKAAR, OF KENYON, MINNESOTA.

AUTOMATIC WAGON-BRAKE.

SPECIFICATION forming part of Letters Patent No. 650,278, dated May 22, 1900.

Application filed June 29, 1899. Serial No. 722,224. (No model.)

To all whom it may concern:

Be it known that I, ED SKAAR, a citizen of the United States, residing at Kenyon, in the county of Goodhue and State of Minnesota, have invented certain new and useful Improvements in Automatic Wagon - Brakes; and I do hereby declare the following to be a full, clear, and exact description of the invention, such as will enable others skilled in the art to which it appertains to make and use the same.

My present invention relates to brakes for wagons and other wheeled vehicles, and has for its object to improve the construction of the same with a view of making the same more universally automatic to perform the various functions required of brakes of the character illustrated and claimed in my prior patent, No. 589,512, of date September 7, 1897, entitled "Automatic wagon-brake." In my said prior invention the brakes were automatically set in going downhill by the pull-back action on the draft-rigging; but it was in the nature of that device that the brakes would also be set when backing the wagon, and hence it was necessary to throw the automatic brake out of action before the wagon could be backed.

The salient feature of my present invention consists in the provision of a device whereby all of the required actions of the brake device are performed automatically.

The preferred form of my invention whereby I accomplish the above object is illustrated in the accompanying drawings, wherein like characters indicate like parts throughout the several views.

Figure 1 is a plan view of a wagon running-gear equipped with my improved automatic brake, some parts of the wagon being broken away. Fig. 2 is a longitudinal vertical section taken approximately on the line $x^9 x^2$ of Fig. 1. Fig. 3 is a broken view, on an enlarged scale, taken approximately on the line $x^3 x^4$ of Fig. 1 and illustrating the position of the parts when the wagon is being backed by the draft-animals. Fig. 4 is a view corresponding to Fig. 3, but illustrating the position of the parts when the brake is set. Fig. 5 is a vertical section taken approximately on the line $x^5 x^6$ of Fig. 1 and illustrating the rela-

tion of the parts shown when the wagon is being drawn in the ordinary manner. Figs. 3^a and 4^a are views corresponding to Fig. 5, but illustrating the positions of the parts when the brake-rigging is in the positions shown, respectively, in Figs. 3 and 4. Fig. 6 is a vertical section taken approximately on the line $x^6 x^6$ of Fig. 1, some parts being broken away. Fig. 7 is a transverse vertical section taken on the line $x^7 x^7$ of Fig. 6. Fig. 8 is a detail in vertical section taken centrally through the outer end of the pole and immediate connections, and Fig. 9 is a transverse section taken on the line $x^9 x^9$ of Fig. 8. 65

Referring to the parts of the wagon, a a' a^2 indicate, respectively, the wheels, the axle, and the pole of the front truck, and a^3 , a^4 , and a^5 indicate, respectively, the wheels, the reach-rod, and reach-rod guide-yoke of the rear truck. As shown, the wagon tongue or pole a^2 is pivoted on a rod a^6 and the forward end of the reach-rod a^4 is pivoted to the front truck by a coupling-pin a^7 .

a^8 indicates an ordinary neck-yoke provided with an ordinary pole-ring a^9 , which works on the end of the pole. 75

a^{10} indicates an ordinary two-horse evener to which the whiffletrees (not shown) are attached. This equalizer a^{10} is for the purpose of applying my invention secured to the pole a^2 and to the pole-strap a^{11} by means of a pole-pin a^{12} , which works through a perforation in said equalizer and through longitudinal slots a^{13} and a^{14} , respectively, in said pole a^2 and said strap a^{11} . These slots a^{13} and a^{14} permit the equalizer a limited to-and-fro movement on the tongue, and the lower end of the pin a^{12} depends below the pole. The purpose of this construction will appear later on. 80 85 90

b indicates a brake-beam which extends transversely across the wagon just in front of the rear wheels and is supported on the forwardly-projecting ends of the yoke a^5 , the said yoke being preferably provided with a plate a^{15} , on which said brake-beam slides. Keeper-brackets c , secured on the plate a^{15} , extend over the brake-beam and assist in holding the same in working position, while permitting it to slide to and from the rear wheels. At its ends and coöoperating one with each rear wheel the brake-beam b is provided 95 100

with a pair of brake-shoes b' . Preferably these brake-shoes b' are provided with scraper-springs b^2 , secured to the faces thereof and provided also with wearing-strips b^3 , which 5 are secured to and form linings to the concavities of the scraper-springs b^2 . It will be noted that the upper ends of the scraper-springs b^2 project above the parts b' and b^3 and are turned rearward, so that they will 10 engage the running-faces of the wheels a^3 before the wearing-strips b^3 are thrown into contact therewith and are thus caused to act as scrapers and serve to clean the running-faces of the wheels before the brakes are applied.

15 To operate the brake-beam, a pair of parallel levers f are pivoted at f' , this pivot, as shown, being afforded by the projecting ends of a transverse bar f^2 , secured to the top of the yoke-plate a^5 . Short links f^3 pivotally 20 connect the upper and shorter ends of the levers f with small brackets f^4 , secured to the front face of the brake-beam b , one on each side of its center.

A long push rod or bar g is mounted for 25 endwise sliding movements on the under side of the pole a^2 . As preferably constructed this push rod or bar g is formed in sections adjustably connected, as best shown in Fig. 3, by slots g' in the overlapped portions of 30 said sections and nutted bolts g^2 , which work through the said slots. Further, as preferably constructed this push rod or bar g is provided with side flanges which work in suitable keepers g^3 , that are screwed or otherwise secured to the bottom of the pole, as best shown in Fig. 9, but also in Figs. 3 and 4. The extreme forward end of said rod g works within a suitable seat formed within the pole-casting a^6 , which casting is thus 40 made to serve as a guide for the said rod. Immediately rearward of the under flange of the said casting a^6 the push-rod g is provided with a depending lug g^4 , which limits the inward movement of the neck-yoke ring a^9 and 45 against which the said ring acts in backing the wagon or in resisting its forward movement in going downhill.

Just below the slot a^8 in the pole a^2 the push-rod g is provided with a reinforced per- 50 foration or seat g^5 , through which the depending end of the pole-pin a^12 is passed. In this manner the push-rod g and the equalizer a^10 are connected for sliding movements together longitudinally of the pole.

55 To a bracket h , rigidly secured to the front axle a' , is a lever g^6 , pivoted at its intermediate portion. The upper end of this lever g^6 is connected to the rear end of the push-rod g by a link g^7 , which is preferably formed 60 in sections, adjustably secured by means of slots g^8 in the overlapped portions of said sections and short nutted bolts g^9 , passed through the said slots. The lower end of the said lever g^6 is connected to the lower ends 65 of the pair of levers f by a connection consisting of a bracket g^{10} , pivoted to the said levers f , and a rod g^{11} , pivoted to the said le-

ver g^6 , and adjustably secured to the said bracket 10 by means of a set-screw g^{12} or otherwise.

With the construction above described it is evident that whenever a backing strain is produced on the push-rod g , such as would be the case either in attempting to back the wagon by the team hitched thereto or by the hold-back action in resisting the forward movement of the wagon in running downhill, the said rod will be pushed rearward, and through the intermediate lever connections the brake-shoes will be forced against the rear wheels a^3 . In resisting the movement of the wagon in running down a steep grade the above action is of course just what is desired; but it is not desirable that the brakes be set when attempting to back the wagon. 85 To prevent the brakes from being thus set in backing the wagon, I employ the device already referred to and which in its preferred form is illustrated in the drawings. This device really comprises a lock or stop which 90 normally prevents the setting of the brakes and a trip which is caused to trip the said lock and thus permit the brakes to be set at such times as the back thrust is thrown onto the push-rod while the wagon is being 95 moved forward or as would be the case in running down a steep grade. The so-called "lock" or "stop" in this preferred construction comprises a rod or rocker p , which is suitably mounted in projections p' from the bracket h , and a bearing p^2 on one end of the front axle a' . Directly over and in line with the upper end of the lever g^6 the rod p is provided with a stop arm or projection p^3 , the free end of which is adapted to engage with the upper end of said lever g^6 and with a shoulder or lug p^4 on the upper end of said lever. At its outer end the rod p is provided with a crank-arm or offset portion p^5 . On the inner end of the hub of the adjacent 110 front wheel a I secure one or more (as shown and preferred a pair) trip devices, which in this preferred construction are formed by cam-sections t of a band t' , which is securely held to the said wheel-hub by a set-screw t^2 115 or otherwise. The cam-sections t are located diametrically opposite to each other, and they are offset inward from the body of the band or ring p' and are both positioned to run in engagement with the projecting crank-arm 120 p^5 of the stop or lock rod p' . The more exact relation of the trip-cams t to the trip or crank arm p^5 of the lock or stop device will be brought out in the description of the operation, which will now be given.

Under the ordinary draft strains the equalizer a^{10} , and hence the push-rod g , which is connected for movement therewith, will be drawn forward, and through the intermediate connection the brake-shoes will be positively forced into their extreme released positions shown in Fig. 2, by reference to which it will be seen that the stop-arm p^3 has fallen on the lever g^6 a considerable distance below

the stop shoulder or lug p^4 thereof. When in running down a steep grade the draft-animals pull back on the neck-yoke to resist the forward movement of the wagon, the push-rod g will be forced rearward until the shoulder p^4 of the lever g^6 is brought against the free end of the stop-arm p^3 on the stop-rod p , and this movement of said shaft p will move the trip or crank projection p^5 thereof 10 out of its normal position and into the path of the trip-cams p . Now as the wagon-wheel which carries the said trip-cam is as long as the wagon is advanced moved forward or in the direction indicated by the arrow marked 15 on Fig. 4^a it is evident that the first trip-cam t which engages the said crank or trip arm p^5 will force the same outward, as shown in said figure, and this movement of the said arm p^5 and its shaft p will force the stop-arm 20 p^3 above the shoulder p^4 of the lever g^6 , thus freeing the said lever and permitting the backward strain on the push-rod to become effective through the intermediate connections to set the brakes, as shown in Fig. 4. When the 25 wagon is backed up by the draft-animals, the push-rod g will be forced rearward until the shoulder p^4 of the lever g^6 is brought into engagement with the free end of the stop-arm p^3 , as shown in Fig. 3, by reference to which 30 it will be seen that the movement thus given to the brake-shoes through the intermediate connections thereto is not sufficient to set the brakes or throw the shoes into engagement with the rear wheels. Under this backing 35 action the stop-lever g^6 will not be forced out of engagement with the stop-shoulder p^4 of the lever g^6 for the reason that the trip-cams will in this case be moved backward or in the direction indicated by the arrows marked on 40 Fig. 3^a, so that their engagements with the crank or trip arm p^5 will only tend to force the stop-arm p^3 downward and into tighter engagement with the lever g^6 . Hence it is obvious the brakes will not be set by the ordinary backing action. It is of course evident that whenever the draft strains are ap-

plied to the equalizer it, together with the push-rod g , will be drawn forward, and the brakes and the other parts will be restored to their normal positions. (Indicated in Fig. 2.) 50

From the foregoing description both the generic and specific features of my invention are thought to have been made clear, and it of course follows from what has been said that I do not limit myself to the specific construction illustrated, but, on the contrary, that my invention is capable of considerable modification. The means for rendering the brake completely automatic under all the conditions above noted I consider broadly new. 60

What I claim, and desire to secure by Letters Patent of the United States, is as follows:

1. The combination with a wheeled vehicle and draft-rigging therefor involving an equalizer and a neck-yoke, both mounted to 65 slide on the wagon-pole, of a brake with brake-setting connections involving a push rod or bar mounted on the wagon-pole and connected for sliding movements with said equalizer and neck-yoke, the intermediate lever g^6 pivoted to a suitable support on the front axle, the rod p suitably mounted on the front axle and provided with the stop-arm p^3 and trip-arm p^5 , and one or more trip cams or flanges t carried by one of the wagon-wheels and operating on said trip-arm p^5 , substantially as 70 and for the purposes set forth. 75

2. The combination with a wheeled vehicle and draft-rigging therefor, of a brake, and brake-operating connections between said 80 brake and said draft-rigging involving a push-rod mounted on the pole, connected for movements with said draft-rigging and formed in longitudinally-adjustable sections, substantially as described. 85

In testimony whereof I affix my signature in presence of two witnesses.

ED SKAAR.

Witnesses:

C. A. STROMME,
A. G. HOODE.
